WILFRED NUTT, LOUIS H. KIVETT, AND DON E. SCOTT, OF GRAHAM, NORTH CAROLINA

DEVICE FOR REGULATING THE DRAW-OFF MOTION ON FULL FASHIONED HOSIERY
KNITTING MACHINES

Application filed April 20, 1931. Serial No. 531,532.

The present invention pertains generally to full fashioned hosiery knitting machines and more particularly to a device to be operatively connected to the draw-off mechanism of such machines for progressively lifting a plurality of weights from the tensioning cable of the machine during a knitting operation.

An important object of the invention is to provide, in a manner as hereinafter described, a weight releasing device for the draw-off mechanism on full fashioned hosiery knitting machines embodying a novel construction and arrangement of parts whereby the tensioning cable may be relieved of the weights at any desired time or periods during the knitting operation, the means for engaging and supporting the weights, thereby relieving the tensioning cable thereof, being adjustable.

Other objects of the invention are to provide a device for regulating the draw-off portion on full fashioned hosiery knitting machines of the character described which may be expeditiously connected for operation to a conventional full fashioned knitting machine without the necessity of materially altering said machine structurally, which will be strong, durable, simple in construction, efficient and reliable in operation and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation showing a device constructed in accordance with this invention operatively connected to the draw-off mechanism of a full fashioned hosiery knitting machine.

Figure 2 is a view in rear elevation of the device.

Figure 3 is a view in top plan of the attachment.

Figure 4 is a detail view in horizontal sec-

tion taken substantially on the line 4—4 of Figure 5 looking downwardly.

Figure 5 is a detail view principally in vertical section taken substantially on the line 5—5 of Figure 3.

Figure 6 is a vertical sectional view taken substantially on the line 6—6 of Figure 3.

Figure 7 is a vertical sectional view taken substantially on the line 7—7 of Figure 3.

Figure 8 is a horizontal sectional view taken substantially on the line 8—8 of Figure 1 looking downwardly.

Figure 9 is a fragmentary detail view on an enlarged scale and in rear elevation showing the mounting of the weights on the guide rods and the means for operatively connecting the weights together.

Figure 10 is a detail view in section through one of the weight lugs showing the means for operatively connecting the rods which support the weights thereto.

Figure 11 is a detail view in side elevation of one of the weights.

Figure 12 is a detail view in top plan of one of the weights.

Figure 13 is a detail view in elevation of one of the weight supporting rods.

Figure 14 is a detail view in perspective of one of the adjustable collars.

Figure 15 is a detail view principally in vertical section showing the means of connecting the tensioning cable of the knitting machine to the lowermost weight.

Figure 16 is a detail view in elevation of the reel pulley of the knitting machine.

Figure 17 is a detail view in vertical section through the ratchet wheel which is mounted on one side of the reel pulley and showing, in side elevation, the locking dog which is engaged therewith to hold the weights during a welt turning operation.

Referring to the drawings in detail, it will be seen that the reference numeral 1 designates portions of the frame of a conventional full fashioned hosiery knitting machine having journaled thereon the usual draw-off shaft 2, upon one end portion of which is fixed the conventional reel pulley 3, upon which is windable the tensioning cable 4. The numeral 4' designates the knitting

needles, from which the fabric 5' comes, and this fabric is connected with a strap 6', connected with the shaft 2, to be wound thereon.

A stub shaft 5 is rigidly connected in the usual manner to an upper portion (not shown) of the knitting machine. A grooved pulley 6 is mounted for rotation on the stub shaft 5 between the collars 7, as best seen in Figure 3 of the drawings. A bracket 8 is provided in its intermediate portion with an eye 9 through which the stub shaft 5 extends, the eye 9 being rigidly secured to the shaft 5 by a set screw 10. The bracket 8 includes a downturned portion upon the lower end of which is rigidly mounted in any suitable manner, a horizontally disposed plate 11, having an opening 12 therein. The cable 4 is trained over the idle pulley 6 and depends therefrom through the opening 12.

Upon the opposite sides of the cable opening 12, the plate 11 is provided with openings 13, for the reception of the upper end portions of a pair of vertical spaced parallel guide rods 14. These guide rods 14 are anchored in the openings 13, by set screws 15, which are threaded into the plate 11. The lower ends of the guide rods 14 are anchored in a base plate 16, which is secured in any suitable manner to the floor or other surface.

The cable 4 extends between the guide rods 14, as shown.

A series of weights is mounted for vertical sliding movement on the guide rods 14, all of the weights with the exception of the lowermost thereof being designated by the numeral 17, the lowermost weight being designated by the reference numeral 18, for a purpose which will be presently apparent. All of the weights are provided with a pair of openings 19, for the slidable passage of the guide rods 14 and the weights 17 are provided also with centrally disposed smooth openings 20 through which the cable 4 passes. These openings 20 are much larger in diameter than the cable, and simply afford a passage for the cable, whereby the cable is in no sense operatively connected with any of the weights, except the lowermost weight. As best illustrated in Figure 15 of the drawings, the lowermost weight 18 is provided with a centrally disposed opening 21, the upper portion of which is threaded to receive the externally threaded lower end portion of a coupling tube 22, having a tapered upper end portion 23 for guiding action into the central openings 20 of the weights 17. The coupling tube 22 is adapted to slidably enter the openings 20. The lower end of the cable 4 passes through the tube 22 and is knotted, as at 24, to prevent withdrawal of the cable from the tube 22 and to secure the lowermost weight 18 on the cable.

All of the weights are provided upon their peripheries with outwardly extending lugs 25, which are integral therewith. Each lug 25

has a smooth vertical opening 26 (see Figures 10 and 12) and a vertical threaded opening 27, as shown. A horizontal arm 28, Figures 1, 2 and 7, is rigidly secured, as at 29, to the plate 11 and this arm is provided with a vertical opening in its free end portion for the reception of a weight take-off or supporting rod 30. The rod 30 is connected to the arm 28 for vertical adjustment, and carries upper and lower collars 31, each of which has a set screw 32, for clamping engagement with the rod 30. The rod 30 is preferably stationary, except for adjustments. One of these collars is illustrated in detail in Figure 14 of the drawings. The weight take-off rod 30 is slidably mounted within the smooth opening 26 of the lug 25 of the uppermost weight 17, and has adjustably mounted upon its lower end, a collar 33, which is clamped in the adjusted position by a set screw 34 (see Figure 10). The collar 33 is beneath the lug 25. The collar 33 is identical with the collars 31. As is apparent, the lug 25 of the uppermost weight 17 is engageable upon the top of the collar 33, in a manner to relieve the cable 4 of the load of said uppermost weight. Weight take-off rods 35 have their upper threaded ends engaging in the threaded openings 27 of the lugs 25 of all of the weights 17. Each of the weight take-off rods 35 is slidably mounted within the smooth opening 26 of the lug 25 of the next lower weight, and has adjustably secured to its lower end beneath said lug a sleeve 33, which may be clamped to the rod by a set screw 34.

A ratchet wheel 36 (see Figures 1, 16 and 17) is rigidly attached to one side of the reel pulley 3, and is engaged by a dog 37, which is pivotally mounted at 38, upon a portion of the frame 1, to swing vertically. The dog or pawl 37 engages with the ratchet wheel 36 to positively lock the shaft 2 of the knitting machine against rotation in one direction, due to the action of the weights 17 and 18, when a welt turning operation is to be made.

In operation, as the cable 4 is unwound from the reel pulley 3, all of the weights 17 and 18, at first move downwardly as a unit upon the guide rods 14. When the uppermost weight 17 descends sufficiently, its lug 25 engages the collar 33 of the weight take-off 30, so that the uppermost weight 17 is now supported by the rod 30, thereby relieving the cable 4 of the load of such weight. The remaining weights engage successively the collars 33 on the lower ends of the weight take-off rods 35, as they descend in a manner to successively relieve the cable 4 of the loads of such weights. Thus, when knitting stockings, the loads of the weights are automatically lifted from the tensioning cable 4, at the proper place, and also at the same place in the production of each pair of stockings, thus producing stockings of more uniform length, having more nearly the same count in stitches than is the case when the weights are re-

moved manually by an attendant, as at present.

- From the foregoing description, it will be seen that the several weight take-off rods support the weights as they reach their lowermost positions, thereby removing the loads from the cable. All of these rods, excepting the uppermost rod, are vertically movable with the weights, during a part of their travel.
- 10 The rods which thus constitute the supporting means for the weights are spaced from and free from connection or engagement with the cable.

It is believed that the many advantages of a device constructed in accordance with the present invention will be readily understood, and although the preferred embodiment of the invention is as illustrated and described, it is to be understood that changes in the design of construction may be had which will fall within the scope of the invention as claimed.

Having thus described our invention, what we claim is:

- 25 1. The combination with a full fashioned knitting machine including a rotary draw-off element, of a cable connected with the element to turn the same, guide means engaging the cable, a plurality of superposed weights with the lowermost weight connected with the cable, the arrangement being such that the lowermost weight raises all of the remaining weights, means to limit the downward travel of the upper most weight and to support the same at the end of its travel, and means to support the remaining weights from the uppermost weight when such remaining weights have descended to the lowered positions.

2. A cable for connection with the draw-off means of a full fashioned knitting machine, guide means engaging the cable, a plurality of superposed weights with the lowermost weight connected with the cable, the arrangement being such that the lowermost weight raises all of the remaining weights, means separate from the cable to limit the downward travel of the uppermost weight and support the same at the end of its downward travel, and means to support the remaining weights from the uppermost weight when such remaining weights have descended to the lowered positions, the last named means being separate from the cable and embodying generally vertical elements there being relative longitudinal movement between the generally vertical elements and certain of said remaining weights.

3. A cable for connection with the draw-off means of a full fashioned knitting machine, guide means engaging the cable, a pair of superposed weights, means whereby the cable is capable of raising the lower weight, means to limit the downward movement of the upper weight and to support the same in the lowered position, and slidable

connecting means between the upper and lower weight so that the lower weight may move downwardly with relation to the upper weight and be supported in the lowered position from the upper weight.

4. A cable for connection with the draw-off means of a full fashioned knitting machine, guide means engaging the cable, a pair of superposed weights, means whereby the cable is capable of raising the lower weight, means to limit the downward movement of the upper weight and to support the same in the lowered position, and a generally vertical element connected with the upper and lower weights and so correlated with said weights that the lower weight may descend with relation to the upper weight and be supported in the lowered position from the upper weight.

5. A cable for connection with the draw-off means of a full fashioned knitting machine, guide means engaging the cable, upper and lower weights so arranged that the upper weight is raised by the lower weight, means whereby the cable is capable of raising the lower weight, means to limit the downward movement of the upper weight and to support the same in the lowered position, and a generally vertical rod connected with the upper and lower weights and having a stop element, the arrangement being such that there is relative vertical movement between the rod and one weight, so that the rod supports the lower weight from the upper weight when it descends to the lowered position.

6. A cable for connection with the draw-off means of a full fashioned knitting machine, guide means engaging the cable, upper and lower weights so arranged that the upper weight is raised by the lower weight, means whereby the cable is capable of raising the lower weight, means to limit the downward movement of the upper weight and to support the same in the lowered position, and a generally vertical rod connected with the upper weight and having a slidale connection with the lower weight and provided with a stop element to limit the travel of the lower weight and to support the same from the upper weight.

7. The combination with the draw-off means of a full fashioned knitting machine, of a cable connected with such means, guide means engaging the cable, a plurality of weights to move the cable in one direction and arranged in superposed relation so that the lowermost weight is capable of raising the remaining upper weights, means to limit the downward travel of the uppermost weight and support the same, and extent of travel regulating connecting elements connecting the downwardly successive weights and being separate from the cable, the arrangement being such that the weights beneath the up-

permost weight are supported from the up-
permost weight when they reach the end of
their downward travel.

In testimony whereof we affix our signa-
tures.

WILFRED NUTT.
LOUIS H. KIVETT.
DON E. SCOTT.
